Inventor:

William F. Helmond
by D. C. Stickney
Attorney

UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

SHIPPING CASE.

Application filed September 28, 1922. Serial No. 531,064.

To all whom it may concern:

Be it known that I, WILLIAM F. HELMOND, a citizen of the United States, residing in Hartford, in the county of Hartford 5 and State of Connecticut, have invented certain new and useful Improvements in Shipping Cases, of which the following is a specification.

This invention relates to shipping cases 10 for typewriters, and has for its object the production of a shipping case suitable for use in shipping typewriters either before or after their rubber feet have been attached to them.

15 In my prior application, Serial No. 389,345, filed June 16, 1920, I have described a shipping case suitable for shipping typewriters with their rubber feet unattached. This shipping case had a bottom of sheet- 20 metal and bosses were pressed up from the bottom for supporting a typewriter by its legs. These bosses were pressed up far enough to cause the typewriter to be supported a sufficient distance above the bottom 25 to permit the portions of the machine which extend below the frame to clear the bottom of the case. Holes were drilled through the tops of these bosses in positions adapting them to be aligned with the holes provided 30 in the legs for the attachment of the rubber feet to the machine.

In accordance with one feature of the present invention, this same general plan of construction is followed, but the bosses are 35 not pressed up to so great a height, and depressions are made in the bottom for receiving the parts which project below the frame of the machine. In this manner, the drawing of the metal to provide clearance 40 for the underslung parts of the machine is divided between the raised bosses and the depressions, so that the metal need not be drawn so fine as before. The exterior surface of the bottom is made generally con- 45 cave, so that the humps on the exterior formed by the depressions within do not extend as far down as the lower extremities of the walls.

In order to adapt the case for shipping 50 typewriters back to the factory with their rubber feet attached, additional holes are bored in the bottom, which are arranged to be aligned with the usual desk screw holes in the typewriter frame. Since these holes 55 are not intended to be used in the original

shipment of a typewriter before its rubber feet have been attached, removable plugs are inserted in them to prevent the ingress of dirt and water to the case.

A feature of the invention is the provision 60 of the holes in the bottom arranged to be aligned with the desk screw holes in the typewriter frame, in combination with the raised bosses which space the typewriter frame a sufficient distance from the bottom 65 to permit the desk screws to be used in attaching the typewriter to the bottom of the case.

Other features and advantages will hereinafter appear. 70

In the accompanying drawings,

Figure 1 is a vertical transverse section of a shipping case, showing a typewriter enclosed therein, with its legs secured to the bottom by screws passing through the holes 75 in the bosses.

Figure 2 is a fragmentary view, similar to Figure 1, showing a typewriter, with its rubber feet attached, secured to the bottom by screws threaded into the desk screw holes 80 of the machine.

Figure 3 is a perspective view of the bottom of the case.

The shipping case 10 comprises a front wall 11, a rear wall 12, side walls 13, a top 85 or cover 14, and a bottom 15 of sheet-steel or other suitable material. The bottom consists of flanges 16, which are attached to the lower ends of the side, front and rear walls by screws 17, and a body-portion 18 90 which lies entirely above the lower extremities of the walls. Four bosses 19 are pressed up from the bottom, and have holes 20 therein for the passage of screws 21. When these holes are used, the screws 21 95 are threaded into holes 22 formed in the typewriter legs for the attachment of the rubber feet 23. Depressions 24 and 25 are formed in the upper face of the bottom 15 to give clearance, respectively, to the back-spacing lever 26 and to a small yoke 27 which extends downwardly below the machine frame 28 and surrounds certain elements of the back-spacing mechanism. Two holes 29 are drilled in the bottom 15 in 100 positions such that they may be aligned with the threaded holes 30 customarily provided in the machine frame for attaching the typewriter to a desk. These holes 29 are filled with plugs 31 of any suitable 110

material, which may be readily knocked out when it is desired to use the holes.

When a typewriter is originally shipped from the factory, it does not have the rubber feet 23 attached to its legs, and the screws 21, which pass through the bosses 19, are used for attaching the machine to the bottom of the case. Since water and dirt might enter the case through the holes 29 and cause damage, the holes are plugged at this time. When it is desired to ship the machine back to the factory for repairs, this may be done by simply knocking out the plugs from the holes and using the desk screws 32, by which the typewriter has been attached to a desk, to secure it to the bottom of the shipping case. The bosses 19 and rubber feet 23 space the typewriter frame a proper distance above the bottom to permit these screws to be used. A block 33 may advantageously be interposed between the frame of the typewriter and the bottom of the case, having holes 34 through which the screws 32 may pass. This lessens the strain upon the screws 32, the typewriter frame and the bosses 19.

Variations may be resorted to within the scope of the invention, and portions of the improvements may be used without others.

Having thus described my invention, I claim:

1. A shipping case for a typewriter having legs with holes drilled therein to receive screws for attaching rubber feet thereto, and having a plurality of threaded holes in its frame for receiving desk screws, said case comprising a sheet-metal bottom having holes arranged to be aligned with the holes in the typewriter legs and to receive screws for securing the typewriter to the bottom prior to the attachment of the rubber feet to the typewriter legs, and having plugged holes arranged to be aligned with the holes in the typewriter frame and to receive screws for securing the typewriter to the bottom when the holes in the typewriter legs have been rendered unavailable by the attachment of the rubber feet thereto.

2. A shipping case for a typewriter having legs with holes drilled therein to receive screws for attaching rubber feet thereto, and having a plurality of threaded holes in its frame for receiving desk screws, said case comprising a sheet-metal bottom having bosses pressed up therefrom with holes through their top walls arranged to be aligned with the holes in the typewriter legs and to receive screws for securing the typewriter to the bottom when the rubber feet are unattached to the typewriter legs, and having plugged holes arranged to be aligned with the threaded holes in the typewriter frame and to receive screws for securing the typewriter to the bottom when the holes in the typewriter legs have been rendered un-

available by the attachment of the rubber feet thereto.

3. A shipping case for typewriters, comprising walls and a bottom having a concave exterior, said bottom being provided with sets of holes adapting it to be secured to a typewriter by either of two alternative methods, and removable plugs in the holes of one set to prevent the ingress of dirt and water when that set is not in use. 75

4. A shipping case for typewriters, comprising walls, a sheet-metal bottom, bosses pressed up from the bottom to support the legs of the typewriter, the bosses having holes arranged to be aligned with holes in the typewriter legs, the bottom having holes arranged to be aligned with desk screw holes in the typewriter frame and having a depression in its upper face to receive a portion of the typewriter which extends below the frame, the depression in the upper face of the bottom forming a hump on its lower face, the bottom being generally convexed upwardly to cause the hump on its lower face to lie above the lower extremities 90 of the walls, and removable plugs in the desk screw holes of the bottom to prevent ingress of dirt and water when they are not in use. 85

5. A shipping case for shipping typewriters before and after the attachment of rubber feet to the legs thereof, comprising a sheet-metal bottom provided with holes arranged to be aligned with holes in the typewriter legs, and also provided with holes arranged to be aligned with desk screw holes in the typewriter frame. 95

6. A shipping case for a typewriter having a plurality of threaded holes in its frame for receiving desk screws, said case comprising a sheet-metal bottom having holes arranged to be aligned with the desk screw holes in the typewriter frame, and bosses pressed up from the bottom for supporting the typewriter by its legs a proper distance above the bottom to permit the desk screws to be used for securing the bottom to the typewriter frame. 105 110

7. A shipping case for typewriters, comprising walls, a bottom secured thereto, and means on the bottom arranged to support the typewriter and to space it from the bottom a predetermined distance, the bottom being provided with holes arranged to be aligned with threaded desk screw holes in 115 the typewriter frame. 120

8. A shipping case for a typewriter, comprising lateral walls and a pan-shaped sheet-metal bottom convexed upwardly to position its general body-portion above the 125 lower extremities of the lateral walls, the bottom having bosses pressed up from it for supporting the legs of the typewriter to space the typewriter upwardly from the bottom, and having shallow depressions ar- 130

ranged to receive portions of the typewriter which project below the typewriter frame.

9. A shipping case for shipping typewriters before and after the attachment of 5 rubber feet to the legs thereof, comprising a sheet-metal bottom convexed upwardly and having holes arranged to be aligned with threaded openings in the typewriter frame, bosses pressed up from the bottom 10 and having holes arranged to be aligned with holes in the typewriter legs, and depressions formed in the convex side of the bottom to receive parts of the typewriter which project below the frame.
- 15 10. A shipping case for a typewriter, comprising walls and a bottom consisting of
- flanges connected to the lower ends of the walls and a body-portion convexed upwardly to lie entirely above the lower extremities of the walls, the body-portion having bosses 20 pressed up from it with holes drilled therein to be aligned with holes in the typewriter legs, and the body-portion also having a depression formed in its convex surface to receive a portion of the typewriter which extends a substantial distance below the typewriter frame. 25
